Attorney.

UNITED STATES PATENT OFFICE.

MARC DIAMOND, OF NEW YORK, N. Y.

PANTOGRAPH.

SPECIFICATION forming part of Letters Patent No. 310,186, dated January 6, 1885.

Application filed March 24, 1884. (No model.)

To all whom it may concern:

Be it known that I, MARC DIAMOND, of the city, county, and State of New York, have invented new and useful Improvements in Pantographs; and I do hereby declare that the following is a full and exact description thereof, reference being had to the accompanying drawings, and to the letters of reference marked thereon, making a part of this specification.

10 The object of my invention is to so brace and strengthen the pivotal joints of a pantograph and steady and support its outer free end, carrying the pencil, as to render the instrument more exact and precise in execution and more durable.

15 It consists in the combination of a wide base or rest with the end of the outer swinging arm which carries the pencil; in the construction of a tubular holder and spring for adjusting the 20 pencil, and in the special formation, as herein-after described, of the supporting or pivotal bearing by which the fixed end is attached to and allowed to swing above the drawing board or table, and of the pivotal joint carrying the 25 tracing-point.

25 In the accompanying drawings, Figure 1 is a plan view of a pantograph with my improved attachments; Fig. 2, a sectional view on line x x of Fig. 1, showing the pivotal attachment whereby the device is secured to the table; Fig. 3, a vertical section on line y y of Fig. 1, illustrating the pivotal joint carrying the tracing-point; and Fig. 4, a vertical section on line z z of Fig. 1, illustrating the end support and the spring-actuated mechanism for adjusting the pencil.

35 A is the first or inner arm, and A' the outer working-arm, of the pantograph, and A² and A³ its intersecting controlling-arms. The first 40 arm, A, of the pantograph is attached to a bearing and brace block, a , Fig. 2, adapted to receive and swing freely upon a long vertical pivot-pin, B, projecting from a circular disk, b, adapted to rest upon the table or board upon 45 which the instrument is to be used and to which it is made fast by means of a wood-screw, b', projecting centrally from its under side.

50 Arms or offsets b² b³ are formed upon the rim of the disk b, to give it an additional bearing-surface upon the top face of the table and facilitate screwing it down thereon. The width

or height of the brace-block a is such as to provide a long extended bearing therefor upon the pivot-pin B, which enables it to support the swinging arm A in its free position above the 55 board without the need of any additional supporting devices in the length thereof, as is found in other pantographs. The pivot C, Figs. 1 and 3, of the jointed controlling-arms A² A³, is formed to project from the enlarged end of a tapering pin, c, which serves as the tracing-point for the instrument. The wide end of the pin c forms a shoulder about the base of the pivot C, and is extended by means of an encircling flange, c', adapted to bear against and support 60 the under side of the lower controlling-arm, A³. The pivot C is threaded at its outer end to screw into a plate or nut, c², made fast upon the top of the end of the upper arm, A². A shoulder, d, formed upon the body of the pivot 70 C, limits the depth to which it may be screwed into the nut or plate c², so as to prevent any binding of the pivotal joint between the arms.

To the under side of the free end of the outer arm, A', carrying the pencil, is fitted and firmly 75 secured a supporting-block, D, having a wide base extending laterally at right angles to the length of the arm, adapted to so support the arm in its movements over the table or paper, and prevent, by its broad even bearing, any 80 rocking or twisting of the arm or tipping of the pencil carried thereby. The pencil is mounted at the end of this arm A' within a slotted tube, E, whose lower end is adapted to screw into and through the arm and its supporting-block, as shown in Fig. 4, so as to afford a long-extended bearing for the pencil, 85 which is free to drop through it and rest upon the table or paper beneath. The upwardly-projecting portion of the tube E is surrounded 90 by a spiral spring, F, coiled loosely thereon, and the lower end of this spring is made fast to an annular disk or thumb-plate, G, encircling the tube E upon the top of the arm, and which is held in place by an annular plate or 95 disk, H, fixed to the tube. A laterally-projecting pin, I, is fixed to the pencil near its upper end to pass into the slot and project out through the same between the coils of the spring, so that as the spring is revolved in the 100 one direction or the other by means of the thumb-plate G its spiral coil engaging the pin

will cause the pencil to move up or down, so that its point may be thereby adjusted to bear upon the paper with more or less pressure.

My improved pivotal attachment gives to 5 the pantograph, by reason of its extended bearing upon the pivot-pin B, a firm, accurate support, whereby it may swing over the paper at the proper elevation without additional support, while the extended base furnished by the 10 block D at the free end of the device, and the firm support given to the pencil by means of the tube E, serve to maintain it invariably in its proper vertical position, thus rendering the whole device more accurate than the pantograph heretofore in use.

15 The tracing-point *c* may be made of hard rubber, and, as it serves as a pivot for the controlling-arms, the latter are always properly centered thereby. Moreover, by making the 20 upper end of the point fast to the upper arm so that it may serve as a pivot for the lower arm, the difficulty which results from the loosening of the joint in the pantographs heretofore constructed by reason of the working loose of the 25 nut upon the upper end of the point when the upper arm is free to move under it is wholly obviated, and the joint remains constantly firm and reliable.

I claim as my invention—

30 1. The combination, with the outer end of the pencil-arm of a pantograph, of a supporting-block, D, secured thereto, the longer horizontal axis of which is at right angles to the

length of the arm, and adapted to slide upon the surface over which the arm is extended, and thereby prevent a rocking of the arm, substantially in the manner and for the purpose herein set forth.

2. The combination, with a longitudinally-slotted tube, E, secured to the pencil-arm of a pantograph to project upwardly therefrom and receive and guide its pencil, of a spiral spring, F, encircling the tube, secured at its lower end to a ring or collar, G, rotating upon the tube, and whose coils are adapted to engage a pin 40 45 projecting from the pencil through the slot in the tube, substantially in the manner and for the purpose herein set forth.

3. The combination, with the joint at the intersection with each other of the controlling-arms A² A³ of a pantograph, and with a detachable tracing pin or point, C, adapted to serve as the pivot for said joint, of a nut or threaded socket, C², rigidly secured to the upper superimposed arm, so as to engage and 50 55 hold the pin upon which the lower arm only is left free to turn, substantially in the manner and for the purpose herein set forth.

In testimony whereof I have signed my name to this specification in the presence of 60 two subscribing witnesses.

MARC DIAMOND.
